UNITED STATES PATENT OFFICE.

AGOSTINO ROGATI AND LOUIS ARONNE, OF NEW YORK, N. Y.

AUTOMATIC STOP FOR PHONOGRAHS.

Application filed August 18, 1919, Serial No. 318,200. Renewed October 11, 1922. Serial No. 593,865.

To all whom it may concern:

Be it known that we, AGOSTINO ROGATI and LOUIS ARONNE, citizens of the United States, and residents of the city of New York, borough of Manhattan, in the county and State of New York, have invented a new and useful Improvement in Automatic Stops for Phonographs, of which the following is a full, clear, and exact description.

This invention relates to automatic stops for machinery and has particular reference to means to automatically stop the rotation of the turntable of a talking machine or phonograph when the end of a record is reached or at any other desired time.

Among the objects of the invention is to provide a brake for co-operation with the turntable of a phonograph, said brake having devices associated therewith to initiate the gripping action thereof automatically according to the position to which the tone arm of the machine has approached in the normal running operation of the machine.

Another object of the invention is to provide an automatic brake or stopping device that is composed of the smallest possible number of parts and which will operate with absolute precision and reliability, the brake mechanism being not dependent upon the action of springs or other parts that are liable to become out of order.

A further object of our invention is to improve the construction of the tone arm base with special reference to its co-operative relation with the automatic brake mechanism.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view of our improvement with the parts in running position and with the tone arm presumed to be swinging toward the left or toward the center of the turntable.

Fig. 2 is a vertical sectional view on the line 2—2 of Fig. 1.

Fig. 3 is a plan view showing the stopped position of the parts.

Fig. 4 is a vertical sectional detail on the line 4—4 of Fig. 3; and

Fig. 5 is a plan view of the tone arm base.

Referring now more specifically to the mechanism we show a phonograph having a turntable 10 to support a disk record 11 in the usual manner and with the spiral groove of which the reproducer 12 co-operates tending to swing the tone arm 13 toward the center 14 of the turntable as a result of the rotation of the turntable in the direction indicated all as is well understood.

The brake comprises a base plate 15 secured as by screws 16 rigidly to the deck 17 of the machine below the turntable and where it is largely invisible or at least inconspicuous. The movable parts of the brake are three in number only and comprise a bell crank 18 pivoted at 19 to the base plate beneath the turntable. The longer arm of the bell crank terminates in a handle 20 and the shorter arm of the bell crank has jointed connection at 21 with the shorter arm of a lever 22 mounted on a fixed pivot at 23 on a rearwardly projecting end 24 of the base plate. The bell crank arms arranged at an acute angle to each other or just slightly less than 90 degrees so that while the axis of the longer arm coincides with the radius of the turntable in the position shown in Fig. 1, the axis of the shorter arm lies outward beyond the line joining the centers of the pivots 19 and 23. While the exact form of this bell crank is not essential we find that by arranging the two arms at an acute angle as indicated the jointed connection between the shorter arm of the bell crank and the lever 22 will serve as a limiting stop to prevent the longer arm from swinging rearward beyond said radius.

The third main part of the brake consists of a shoe 25 preferably in the form of a cylindrical roller fixed by means of a vertical pin 26 to the upper surface of an arm 27 pivoted at 28 to the longer arm of the bell crank. The pivot 28 is provided with a spring or friction washer 29 whose function is to hold the arm 27 against the bell crank

with sufficient friction to provide for the releasing of the shoe from the periphery of the turntable in the starting of the motor by simply drawing rearward on the handle 20. 5 The arm 27, however, is provided with a finger piece 30 for the manipulation of the brake shoe in adjusting the device. The base plate 15 is shown provided with a rib 31 upon which the bell crank glides and 10 whereby the bell crank is held for steady movement in a definite plane around its pivot 19 and without unnecessary friction or resistance. The pivots 19, 21 and 23 are all relatively free or easy moving, when the 15 arm 27 lies in or coincides with the axis of the longer arm of the bell crank when the latter lies in the radius of the turntable. As shown in Fig. 1 the shoe 25 has its greatest clearance with respect to the turntable. If 20 the arm 27 be moved around its pivot 28 in either direction from this position it will be carried toward or into contact with the periphery of the turntable. Again, if the bell crank is swung around its pivot 19 the arm 25 27 due to the friction at the pivot 28 will be carried with it and likewise brought toward or against the periphery of the turntable, although the approach of the shoe toward the 30 periphery of the turntable under the latter circumstance will be more gradual than when the arm is swung directly around its own pivot 28.

The rear free end of the lever 22 extends 35 into proximity to the base 32 of the tone arm. Said tone arm base is an annular member having a flange 33 of substantially cylindrical form projected downward into the opening in a collar 34 fixed as by means of screws 34' to the deck of the phonograph. 40 The opposing cylindrical faces of the flange 33 and collar 34 are provided with raceways for a series of anti-friction balls 35 spaced from one another by any suitable spacing means such as coil springs 36. The base 32 45 has an external flange 32' overlapping the upper part of the collar and serving not only as a neat finish for the base, but as a means to exclude dust or dirt from the bearings. The balls are inserted into the raceways 50 through registering notches or holes which are thereafter closed by a plug 37 locked to the bottom of the base 32 by means of a screw or the like 38. The plug 37 has a lip 39 projecting outward radially from the 55 base and operating in an arc-shaped recess or notch 40 formed in the bottom of the collar 34 whereby the rotation of the tone arm is limited. The tone arm is pivoted on coaxial pivots 41 in the upper flange portion of the 60 base 32 so as to provide for the vertical rocking movements of the tone arm which are necessary in the manipulation of the reproducer in practice. The pivots arranged as shown insure, however, that the base 32 65 will rotate positively as a result of the

swinging of the tone arm in either direction. Consequently when the needle carried by the reproducer co-operates with the record groove on the disk and the turntable rotates the disk the tone arm will be swung toward the left as shown in Fig. 1 and the tone arm base will be correspondingly rotated. 70

The base 32 carries a lug 42 adapted to co-operate with the rearwardly projecting end of the lever 22 as the reproducer approaches the end of the record groove, and this co-operation serves to cause the bell crank to swing toward the right as indicated in Fig. 1 and the brake shoe to come into frictional contact with the periphery of the 75 turntable. The instant this frictional contact between the brake shoe and the turntable takes place the turntable causes the shoe arm 27 to swing quickly around its pivot 28 and instantly lock the turntable 80 from rotation due to the gripping or wedging action so set up between the shoe and the turntable. In other words whenever the 85 brake shoe is swung from the normal spaced position so as to contact with the periphery 90 of the turntable the rotation of the turntable will automatically cause the brake to act to stop it.

To determine the time of the automatic action of the brake in accordance with different sizes of records or records having different spaces between the ends thereof and the center of the turntable the procedure is as follows: Assuming that the brake is set and holding the turntable from rotation as 100 in Fig. 3, the arm 27 will lie in a direction oblique to the radius of the turntable. The axis of the longer arm of the bell crank may be parallel to that of the arm 27 or it may be different therefrom according to a previous manual adjustment. Irrespective therefore of the position of the bell crank the operator after placing a record upon the turntable will carry the needle thereof to or adjacent to the last coil of the record groove 105 and while doing so with his right hand will grasp the handle 20 with his left hand and will swing the bell crank thereby to bring the rear end of the lever 22 against the lug 42. During this manipulation of the bell 110 crank the operator will hold the brake shoe by his thumb so as to maintain the contact thereof with the turntable, thereby preventing the premature starting of the motor. This simple holding of the finger piece 30 by 115 the thumb so as to maintain the holding contact or grip of the shoe upon the turntable is the only manipulation required of the brake shoe. After adjustment as above indicated the operator will carry the reproducer out to the beginning of the record groove and apply it in the usual manner and will start the motor by a simple rearward swing of the bell crank handle 20. The friction at the joint 28 will cause the brake shoe 120

125

130

to be carried away from the turntable coincidentally with the movement of the bell crank. With the swinging of the bell crank toward the left as just stated the rear end 5 of the lever 22 will swing toward the right and to a multiplied distance due to the disparity in lengths of the two arms of the lever 22. Thus the point or rear end of the lever will be moved far enough to the right 10 so that the lug 42 while moving in the playing direction with the tone arm will engage the lever and cause it to move toward the left for a material length of time before the brake will be set, but by the time the lug 15 reaches the position indicated in Fig. 3 which corresponds to the end of the record groove the brake shoe will have been carried into contact with the turntable by virtue of the adjustment previously given thereto. 20 Consequently the brake will act automatically at a precise predetermined time in accordance with the most simple kind of manual adjustment. The brake device is provided with no springs nor any other 25 means that will tend to cause a snapping or jerking movement of the brake shoe at any time. The brake therefore acts quietly as well as promptly and can never fail to operate or get out of order.

30 We claim:

1. In an automatic stop, the combination of two levers mounted to oscillate around fixed pivots and jointed together whereby the oscillation of either lever in either direction 35 will cause a corresponding oscillation of the other lever in the other direction, a friction brake shoe and an arm carrying said shoe, said arm being pivoted to an arm of one of the first mentioned levers remote 40 from the jointed connection between such lever and the other lever, the connection between the shoe arm and the lever carrying it being such that the arm may be moved independently of the lever in the setting of the

brake, and the arm will be carried with the 45 lever automatically with the releasing of the brake.

2. In an automatic stop for phonographs, the combination with a tone arm and the turntable of the phonograph, of a lug extending from the tone arm, a fixed support arranged adjacent the periphery of the turntable, a bell crank lever pivoted to said fixed support in such a manner that the free end of one of the arms of the bell crank lever 50 extend substantially radially of the turntable and the other extends toward said stop, an actuating lever pivoted between its ends onto said support, said lever being of such a length as to extend into the path of movement of said stop and to overlap the second mentioned arm of the bell crank lever, said overlapping portion being provided with a slot, a pin extending through said slot into the bell crank lever, a swinging member pivotally mounted on said bell crank lever, and a brake member carried by said swinging member, said brake member being positioned to engage the periphery of said turntable when said stop has moved the actuating lever 55 and the second mentioned arm of the bell crank lever into an alinement.

3. In an automatic stop for phonographs a fixed plate formed with a pressed up friction member, a bell crank lever pivotally 75 mounted on said fixed plate, a brake swingingly positioned on one of the arms of said bell crank lever, a pin extending from the second arm of the bell crank lever, a lever pivoted between its ends to said plate and 80 arranged so that one end will overlap the second arm of said bell crank lever, said end having a slot for receiving said pin, and a stop actuated by the tone arm of the phonograph for shifting said lever.
